(57) **CLAIM**

The ornamental design for a car body, toy car body replica and/or other replica, as shown and described.

DESCRIPTION

FIG. 1 is a top, front and right side perspective view of a car body, toy car body replica and/or other replica showing our new design, the top, front, and left side perspective view being a mirror image of FIG. 1;

FIG. 2 is a top, rear, and right side perspective view thereof, the top, rear, and left side perspective view being a mirror image of FIG. 2;

FIG. 3 is a right side elevation view thereof;

FIG. 4 is a left side elevation view thereof;

FIG. 5 is a front elevation view thereof;

FIG. 6 is a rear elevation view thereof; and,

FIG. 7 is a top plan view thereof.

The dot-dash broken lines illustrate boundaries of the claimed design and form no part of the claimed design. The dash-dash broken lines illustrate portions of the car body, toy car body replica and/or other replica that form no part of the claimed design.

1 Claim, 7 Drawing Sheets
